UNITED STATES PATENT OFFICE.

NEPHI BRUNKER, OF SWAN LAKE, IDAHO.

RAILWAY-SWITCH.

SPECIFICATION forming part of Letters Patent No. 453,405, dated June 2, 1891.

Application filed July 12, 1890. Serial No. 358,506. (No model.)

To all whom it may concern:

Be it known that I, NEPHI BRUNKER, a citizen of the United States, residing at Swan Lake, in the county of Bingham and State of Idaho, have invented certain new and useful Improvements in Railway-Switches; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to certain new and useful improvements in railroad-switches, and it has for its object to provide suitable means whereby a train may by suitable attachments automatically open or close the switch, and 20 whereby the movement of one only of the opposite points of the switch by means of the switch-lever or its equivalent is necessary, the opposite point being moved by the pressure of the truck-wheels of the locomotive upon 25 the first-named point, thereby obviating the danger resulting from the locomotive jumping the switch; and for this purpose my invention consists in the construction, arrangement, and combination of the parts of which 30 it is composed, as will be hereinafter more fully described and claimed.

Referring to the accompanying drawings, in which corresponding parts are designated by corresponding letters, Figure 1 is a plan 35 view of a switch constructed in accordance with this invention. Fig. 2 is an elevation of one of the switch toggle-joints. Fig. 3 is a detail showing a modified form of a switch-actuating mechanism.

40 The main-track rails A A' are shown in the drawings as forming a junction with the track-rails B B' and C C', the rails A and B and A' and C' being continuous, the said tracks being branched off in opposite directions. The 45 ends of the rails C and B' terminate in spring noses C² and B², the nose B² being longer than the nose C² and being sprung inward opposite the forward end of the nose C², with which it is connected by the cross-piece c.

50 In order to manipulate the switch-noses B² and C², I provide the cross-bar G, crossing the track below the track-rails A A' and switch-

noses C² and B² and connected to the cross-piece c by the link c'. The ends of the bar G are bent upward, each end having two 55 springs g thereon.

J are elbow-levers, pivoted at j to a cross-tie J'. To one of these is connected a slide-bar K, which in turn is connected to one bar K' of a knuckle or toggle joint, whose opposite 60 bar K² is pivoted at l to a cross-tie L. The elbow-lever is provided with a hole at its outer end, through which the switch-rod G passes, the elbow-lever being held between the springs g on the end thereof. At the opposite end of the rod G, which is outside of the rail A and B, the springs g and the elbow-lever J, connecting bar and toggle-joint, are 65 duplicated, this joint being marked M.

To the ends of a tie R links R' have their 70 lower ends pivoted, their upper ends being pivotally secured to the forward end of the depressing-arms R², the rear ends of which rest upon the pins r, projecting from the outer sides of the bars K² of the toggle-joint, and it 75 will be thus readily understood that on depressing either of the said arms the corresponding toggle-joint will also be depressed.

N N are rollers attached to the engine in a position to permit their adjustment, so that 80 they may one at a time be brought into contact with one of the depressing-arms which is up. This causes the knuckles to be pressed down, and consequently lengthened, thus, 85 through the medium of the levers, causing the switch to be operated, as will be further described. When one of the knuckles or toggle-joints is pressed down, the other must rise, and inasmuch as the joint which is down is to all intents and purposes locked against 90 raising it by end-pressure, I provide for raising it otherwise.

O is a rod pivoted in suitable bearings under the rail, having at its ends cranks P P', which set in opposite directions one under the toggle-joint of the right and the other under that of the left, so that when one crank is pressed by the pressure of the roll on the toggle-joint, the other is raised, thus raising the other toggle-joint.

100 It will be understood that when the joint M is depressed the forward end of the nose B² will be snug against the inside of the rail A', while the nose C² will be correspondingly away

from the rails A, as this may be called the "normal position" of the switch. If a locomotive now comes down the track in the direction of the arrow, the forward wheels thereof on the side of the rail A' will strike the inwardly-sprung portion of the nose B² before the wheels upon the opposite side have reached the forward end of the nose C², which will be drawn still farther away from the rail 5

10 A by the connecting cross-piece c, permitting the train to run upon the rails B B'. It will also be evident that if a train coming in the direction of the arrow depresses, by means of its roller, the joint K' K² that the rod G will be thrown over toward the rail A, carrying with it the end of the nose B², (the spring of its spring portion permitting this,) thus opening the tracks C C', the spring of the nose B² holding the nose C² securely against the rail.

15 20 In some cases I may desire to do away with the toggle-joints entirely and manipulate the switches by the ordinary hand or target lever or switch. In such cases I connect the pivoted lever S of the target-switch with the one end of the rod G by means of the rod S', which has bends formed therein, these bends, 25 (as the rod is of spring metal) furnishing the desired elasticity to hold the switches in place, and serving the same purpose as the springs 30 g g upon the rods G.

Having thus fully described my invention, what I claim as new, and desire to secure by Letters Patent of the United States, is—

1. In combination, the switch, the switch-

rod, the elbow-lever, and the toggle or knuckle 35 joint adapted to be depressed by the engine, as set forth.

2. In combination, the switch, its rod, the elbow-levers, the knuckle joints, and the double-cranked rod, whereby the joints are 40 operated in unison, as set forth.

3. In a railway-switch, the combination, with the main-track rails, of two switch-points between the said rails and connected together, one of the said points being sprung inwardly 45 toward the center of the track at a point opposite the extreme end of the opposite point, and track-rails connected with the said switch-points, as described.

4. In a railway-switch, the combination, 50 with track-rails and switch-points, of a rod connecting the said points, an elbow-lever on each side of said track connected with one end of said rod, a toggle-joint connected with each of the elbow-levers, an arm having its 55 rear end bearing upon each of the said joints, a link having its opposite ends pivotally connected to the track-bed and to the forward portion of the said arm, and a rod below the said track, having opposite cranks upon its 60 opposite ends located below the said toggle-joints, as described.

In testimony whereof I affix my signature in presence of two witnesses.

NEPHI BRUNKER.
